UNITED STATES PATENT OFFICE.

PETER ARMBRUSTER, OF MEHLVILLE, MISSOURI, ASSIGNOR OF ONE-HALF
TO HERMAN WIETHOP AND JOHN VENARDE, OF SAME PLACE.

HAND-BRAKE FOR WAGONS.

SPECIFICATION forming part of Letters Patent No. 630,021, dated August 1, 1899.

Application filed May 5, 1899. Serial No. 715,720. (No model.)

To all whom it may concern:

Be it known that I, PETER ARMBRUSTER, a citizen of the United States, residing at Mehlville, county of St. Louis, State of Missouri, have invented a certain new and useful Improvement in Hand-Brakes for Wagons, of which the following is a full, clear, and exact description, such as will enable others skilled in the art to which it appertains to make and use the same, reference being had to the accompanying drawings, forming part of this specification, in which—

Figure 1 is a side elevational view of a wagon, showing my improved band-brake in position thereon. Fig. 2 is a top plan view of the same, the body of the wagon being partly broken away. Fig. 3 is an enlarged side elevational view of the band-brake and its associate parts. Fig. 4 is a sectional view on line 4 4, Fig. 3, showing the hub in elevation. Fig. 5 is a side elevational view of the band-brake and its associate parts as seen from the inside. Fig. 6 is a sectional view, partly in elevation, on line 6 6, Fig. 3. Fig. 7 is a top plan view of the band-brake and its associate parts, and Fig. 8 is a detail view showing the means for securing the band-brake in position on the spring.

This invention relates to a new and useful improvement in band-brakes for wagons, the object being to construct a device of the character described which can be applied to existing forms of wagons without changing any of the parts thereof.

The invention consists in the provision of a brake-tread or friction-band detachably secured to the spokes of the wagon-wheel, in combination with a flexible band-brake having one end secured to a clip, which clip also acts as a fulcrum for the brake-lever, to which lever the other end of said band-brake is connected.

Heretofore band-brakes have been used on wagons in which the friction-band was clamped or secured to the hub of the wheel either by being shrunk or otherwise fastened in position and the band-brake so arranged as to coöperate therewith. These constructions all necessitate the use of a special hub or other device, while my present invention contemplates the application of a band-brake

to an ordinary wagon without requiring any change whatever in its detail. By the use of friction-bands attached directly to the hubs of the wheels, especially where the same is shrunk in position, it has been found that the heat generated would cause said bands to expand so as to become loose. By attaching the friction-band directly to the spokes of the wheels this objection is overcome in my construction.

In the drawings, A indicates the body of a wagon on which is pivotally mounted, preferably in convenient reach of the operator, a lever B, coöperating with a notched segment C, whose function is to hold said lever in its adjusted positions.

D indicates a brake-rod connected to lever B, which brake-rod is attached at its other end to an arm e of a rock-shaft E, which is arranged under the body of the wagon, its arms projecting on each side thereof, so as to apply the brakes on both rear wheels of the wagon. Links F are connected to the arms e, which links are likewise attached at their rear ends to levers G, pivotally mounted in the ends of clips H, said clips being of the following construction. (See Fig. 8.)

A tongue h is designed to rest on the upper face of the semi-elliptic spring I of the wagon, and said tongue passing under the yoke-plate g, which clamps the semi-elliptic spring in position on the axle J by means of the yokes f. This tongue is preferably made as wide as the springs upon which it rests and at its forward end is provided with a down turned projection h' on one side and a corresponding projection h'' on its opposite side parallel to the first-mentioned projection, which projections h' and h'' embrace the springs and hold the forward ends of the tongue in position. The projections h'' are extended laterally, as shown in Figs. 6, 7, and 8, to afford a support for ears h''', in which the levers G are pivoted. The fixed ends of the band-brakes K are likewise secured to these lateral projections, which I have marked h''' in the drawings, and extend under and around the friction-band secured to the rear wheel of the wagon, said band-brake being then secured at its upper end to the lever g above its pivot-point, as shown more clearly in Figs. 1 and

3. I prefer to face the band-brakes on their inner faces with leather or other material to enable them to better grasp the friction-band with which they coöperate.

5 L indicates the rear wheel of the wagon, which is of ordinary construction—that is, consists of the usual hub, spokes, rim, &c.—on which is secured my improved friction-band M. This friction-band, as shown more 10 clearly in Fig. 4, consists of a ring having an inturned flange m, perforated at suitable points for the passage of the parallel members of U-shaped bolts N, which bolts surround the spokes of the wagon and through 15 the medium of nuts on their inner ends tightly bind the ring M in position on the wheel. The exterior face of ring M forms the friction or braking surface with which co- 20 operates the band-brake K, heretofore described.

In placing the ring M in position on the wheel the U-shaped or stirrup bolts are introduced from the outside, so as to embrace alternating spokes, their threaded ends passing through openings in the internal flange m of the ring M, after which the nuts are screwed in position to clamp the parts together.

In operation when it is desired to brake a 25 wagon to which my improved band-brakes are attached the lever B is thrown forward, which tightens the band-brake on the friction-band, as is well understood.

It is obvious that a foot-lever can be used in 30 lieu of the hand-lever B to effect the braking operation.

I am aware that many minor changes in the 35 constructions, arrangement, and combination of the several parts of my device can be made 40 and substituted for those herein shown and described without in the least departing from the nature and principle of my invention.

Having thus described my invention, what I claim, and desire to secure by Letters Patent, is—

1. In a braking apparatus, the combination with a wheel and its axle and springs secured to said axle, of a band attached in position on the spokes of said wheel, a clip secured on said springs and provided with a support for 50 a lever, a band-brake having one end attached to said clip in juxtaposition to said lever-support, and a lever pivotally mounted in said support, to which lever the other end of said band-brake is connected; substantially 55 as described.

2. The combination with a wheel and its axle, of springs secured to said axle, a ring M, having an inturned flange secured to the spokes of said wheel by means of stirrup- 60 bolts, a clip consisting of a tongue attached to said springs, said clip being also provided with downturned portions h' and h'', the latter of which is formed with a lateral projection, a band-brake having one end fixed to said lat- 65 eral projection, a lever pivotally mounted on said lateral projection, and to which lever the other end of said band-brake is connected; substantially as described.

3. The herein-described clip for use in connection with band-brakes, the same comprising a tongue h, and parallel projections h' and h'', from the latter of which extends a lateral projection h''', ears or lugs h''' mounted upon said lateral projections; substantially as de- 75 scribed.

In testimony whereof I hereunto affix my signature, in the presence of two witnesses, this 1st day of May, 1899.

PETER ARMBRUSTER.
